UNITED STATES PATENT OFFICE

2,469,103

YARN BOBBIN

Lyle A. Carlson, Oakville, Conn.

Application March 21, 1947, Serial No. 736,345

4 Claims. (Cl. 242—96)

1

This invention relates to bobbins for holding and dispensing yarn, thread or string, or the like, and particularly one for use where one is hand knitting articles having a variety of colors.

One object of this invention is to provide a bobbin of simple construction which holds yarn without danger of being accidentally unwound, but upon which the yarn is easily wound and from which the yarn may be easily released as used.

Another object is to construct a bobbin of the above character, being of symmetrical shape and comprising a pair of opposed inwardly directed arcuate portions joined by a connecting bar and having their distal ends held in spaced relationship to provide for relatively narrow opposed openings through which the material may be conveniently wound and unwound from the connecting bar. Another feature of this particular construction is that when the bobbin is loaded with yarn or like material it will be off balanced when held in suspended position so that the wound material will not be easily unwound therefrom by accident.

These and other objects will become evident upon inspection of the invention which is shown in the accompanying drawings and described particularly as follows:

Fig. 1 of the drawing is a front view of the bobbin constructed of a thin flat material.

Fig. 2 is a sectional view taken along the line A—A of Fig. 1.

Fig. 2A of the drawing shows a bobbin constructed as in Fig. 1 upon which a quantity of yarn has been wound and which illustrates a typical position assumed by the bobbin while in use.

Fig. 3 is a front view of the bobbin, showing an alternative construction wherein the bobbin is made from material of circular cross section, and

Fig. 4 is a sectional view taken along the line B—B of Fig. 3.

Referring to the drawings, Figs. 1, 2 and 2A show the preferred construction of a bobbin made of flat sheet material and which comprises two arcuate members 10, 10 lying in the same plane with their concave portions opposed and joined at the midpoints of their concave sections by a flat cross or connecting bar 11. The cross bar 11 is of sufficient length to maintain the extreme or distal ends of arcuate members 10, 10 in relative narrow spaced relationship and provide for openings 12, 12. The cross bar 11 together with arcuate members 10, 10 form two semi-circular chamber areas 13, 13 on opposite sides of bar 11, 55

and which areas provide adequate room for the material wound and accumulated upon said bar 11.

In charging the bobbin for use, one end of the yarn or material 14, is first caught upon the cross bar 11 in any convenient manner and then wound about said bar 11 in numerous turns through openings 12, 12 until a sufficient quantity of yarn has been accumulated within the areas 13, 13.

10 In use the bobbin is suspended by the free end of the yarn 14 in the manner as best seen in Fig. 2A. As the yarn is used, additional yarn is released by unwinding manually through the relatively narrow openings 12, 12. A particular 15 feature of this bobbin is that, while in use the bobbin will usually be suspended by the free end of the yarn and in the natural tendency for the yarn to unwind from the ball-like accumulation of yarn on the cross bar 11, the bobbin will seek 20 an off-balanced position so that the openings 12, 12 more frequently will assume any angular position other than the vertical. It is only when openings 12, 12 are in a vertical position that the 25 yarn passes through the openings. Since the openings 12, 12 constitute only a small portion of the total circumference of the bobbin, the mathematical probability of the openings 12, 12 being in a vertical position is small and the possibility 30 of the yarn slipping through openings 12, 12 unless guided by hand is very remote.

In the alternative construction shown in Figs. 3 and 4, the bobbin is of the same symmetrical shape as illustrated in the preferred construction, except here all parts of the bobbin are made of 35 round stock instead of flat stock, and comprises the opposed arcuate portions 10', 10' connected together by the cross bar 11' and allowing for the relatively narrow openings 12', 12' at the extreme ends of said arcuate portions 10', 10'. 40 The usual semi-circular chamber areas 13', 13' are like provided on opposite sides of the cross bar 11' for the accumulation of the material wound upon said bar 11'.

While the bobbin here disclosed in two forms 45 has been designed for use particularly with yarn as a convenience in the knitting of articles employing a variety of colored yarns, it is also within the purview of this invention to employ the bobbin as a holder for carpenter's line cords, 50 plumb bob cord retainers and other uses where it is desired to have a retainer for a quick accumulation or discharge for a cord of general usage, but which cannot be easily and accidentally unwound from the bobbin.

Furthermore, it should be understood that the

sides of the bobbin represented by the arcuate portions 10 and 10' need not necessarily be true arcs, inasmuch as they may be of other shapes but still be symmetrical and joined at their mid portions and with their distal ends in slightly spaced relationship relative to each other and still be within the scope of my invention.

I claim:

1. A bobbin for use with yarn or like material comprising a pair of semi-circular elements, a cross bar joined to said elements at their mid-concave sections and of a length to hold said semi-circular elements so that their adjacent ends are in narrowly spaced relationship but wide enough to allow the material wound on said cross bar to freely pass between said spaced ends, and said cross bar and semi-circular elements lying in a common plane.

2. A bobbin for use with yarn or like material comprising a stamping made from flat sheet material having flat inwardly directed arcuate sections and a flat cross bar joining said arcuate sections at their mid-position and of a length to space the distal ends of said arcuate sections in relatively narrow spaced relationship but wide enough to allow the material wound on said cross bar to freely pass between said spaced ends, and said cross bar and semi-circular elements lying in a common plane.

3. A device of the character described comprising a pair of opposed arcuate members and a cross bar joining said members together with their concave portions in adjacent relationship,

said cross bar and arcuate members being made of flat sheet-like material and lying in a common plane, said cross bar serving as a spool for winding material thereupon, and said arcuate members defining areas within which said material is wound, and the ends of said members being spaced so as to allow the material wound on said cross bar to freely pass therebetween.

4. A device of the character described comprising a pair of opposed arcuate members and a cross bar joining said members together with their concave portions in adjacent relationship, said cross bar and arcuate members being constructed of round stock throughout their entire lengths, said cross bar serving as a spool for winding material thereupon, and said arcuate members defining areas within which said material is wound, and the ends of said members being spaced so as to allow the material wound on said cross bar to freely pass therebetween.

LYLE A. CARLSON.
